UNITED STATES PATENT OFFICE.

ZEBULON WIRT, OF KANSAS CITY, MISSOURI.

GRAIN-STORAGE BIN.

1,372,060.

Specification of Letters Patent. Patented Mar. 22, 1921.

Application filed October 19, 1918. Serial No. 252,851.

To all whom it may concern:

Be it known that I, ZEBULON WIRT, a citizen of the United States, residing at Kansas City, in the county of Jackson and State of Missouri, have invented certain new and useful Improvements in Grain-Storage Bins; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 This invention relates to grain bins and one of the objects thereof is to construct a compartmental storage bin of simple construction but which will efficiently perform the service for which it is intended.

20 In carrying out my invention I prefer to construct a bin in the form of a vertical sectional hollow column, subdivided interiorly by curved walls and a connecting partition in such manner that all of the divisions will be of substantially equal capacity. I also provide means for tying the walls together so that liability of the bin breaking down will be reduced to a minimum if not wholly avoided.

25 In the drawings,

Figure I is a perspective view of an elevator with which two of the bins are associated, part of the wall of one bin being broken away to show the interior construction thereof.

30 Fig. II is a cross sectional view through one of the bins.

Fig. III is a fragmentary perspective view of parts of two of the partition walls and the connecting wall thereof, showing the manner of tying the parts together.

Fig. IV is a sectional view in a slightly modified form of bin.

Fig. V is a fragmentary perspective view 45 of part of the outer circular wall and one end of the curved inner partition wall, showing the vertical tying rods and

Fig. VI is a diagrammatic view of a further modified form of bin.

50 Referring now to the drawings by numerals of reference:

1 designates an elevator on each side of which is illustrated a bin 2. The bin is preferably constructed with a circular wall comprising tiles or building blocks 3 which may

be of any preferred construction but which are preferably hollow as illustrated in detail in Fig. III. The tile are shown as provided with edge grooves 4 and 5 so that when the tile are laid in courses with the joints 6 of one course overlapping those of the other a cement receiving space is provided in which the horizontal reinforcing rods 6 may be placed to be embedded in the cement. The reinforcing rods are preferably of sufficient length to permit a single rod to be laid in the upper groove of the last course of tile with the ends overlapping, as shown at 7, Fig. II. As each circular course of tile is laid a pair of corresponding courses are laid 70 in inwardly projecting arcuate form to provide the walls 9 and 10 and these are connected by the cross wall 11, as shown in Figs. II and III. The inwardly projecting arcuate walls 9 and 10 may be tied to the circular outer wall by the reinforcing rods 12 and 13, the ends of the rods being embedded in the cement in the grooves of the tile 3 forming the outer wall of bin and having greater security. These may be wrapped if 75 desired. The transverse wall 11 is tied to the inwardly projecting arcuate walls 9 and 10 by the reinforcing and bonding rod 14, the ends 15 and 16 of which lie upon the reinforcing and bonding rods 12 and 13 and 80 may be secured by the bonding wires 17.

From the foregoing it will be apparent a bin constructed in accordance with the one just described may be easily assembled and yet be of substantial structure and it will be 85 apparent that the partitions may be so disposed that the bin will be divided in equal compartments, this being desirable in rural districts where each farmer desires to store his grain separately.

90 In the form shown in Figs. IV and V the outer wall of the bin will be provided at the juncture of the arcuate walls with vertical tile 3' so that a vertical wire or bonding rod 18 may be passed through the vertical air 100 space 19 and cross the horizontal circular bonds 6. In this form the bond wires 12 and 13 are passed around the reinforcing rods 6 and have their ends projecting downwardly into the air spaces of the vertical tile 105 as at 20, Fig. V.

95 In Fig. VI I have shown a diagrammatical view of a construction of a plurality of bins in which the inner divisional walls of the end bins are simply a continuation of the 110

outer walls of the intermediate bin. This is a convenient construction where large capacity is required.

What I claim and desire to secure by Letters-Patent is:

1. A grain bin comprising an upstanding circular wall consisting of tile laid in courses, circular bonding rods between the courses, similar arcuate shaped walls within the circular wall at opposite sides of the center thereof and presenting inner convex faces and outer concave faces and having their vertical end edges abutting the inner face of the said circular wall, bonding wires in the arcuately curved walls having their ends parallel with the circular bonding rods, and a cross wall connecting the arcuate walls one to the other between the ends thereof and bonding rods in the cross wall connected to the bonding rods in the arcuate walls.
2. A grain bin comprising a circular outer wall consisting of blocks laid in courses, continuously curved arcuate walls located at opposite sides of the center of the outer wall and having their vertical edges abutting

against the inner face of the outer wall at spaced points, said arcuate walls presenting inner convex faces to each other and consisting of blocks laid in courses and a connecting wall interposed between the arcuate walls between the ends thereof and bracing and holding the same in position to each other and the circular outer wall.

3. A grain bin comprising an upstanding circular wall consisting of tile laid in courses, diametrically opposite, arcuate walls within the circular wall at opposite sides of the center thereof and presenting inner convex faces toward each other and having their vertical end edges abutting the inner face of the said circular wall, the ends of the arcuate walls abutting against the inner face of the circular wall, the arcuate walls being spaced apart, and a transverse wall connecting the two arcuate walls, whereby a substantially H-shaped partition is formed within the upstanding curved wall.

In testimony whereof I affix my signature.

ZEBULON WIRT.
